Primary Examiner — Ian Simmons*Assistant Examiner* — Keith Frank(74) *Attorney, Agent, or Firm* — Ladas & Parry LLP(57) **CLAIM**

We claim the ornamental design for a cold water container for refrigerator, as shown and described.

DESCRIPTION

FIG. 1 is a perspective view of a cold water container for refrigerator showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a cold water container for refrigerator of our new design in use showing the appearance with the cap of the subject design detached.

The broken lines shown in the drawings form no part of claimed design.

1 Claim, 7 Drawing Sheets(56)
